FIG. 8

FIG. 1 is a top plan view of a magnetic variable format appointment board or the like, showing my new design;

FIG. 2 is a bottom plan view;

FIG. 3 is an elevational view of the left-hand side;

FIG. 4 is an elevational view of the right-hand side;

FIG. 5 is an elevational view of the upper end;

FIG. 6 is an elevational view of the lower end;

FIG. 7 is a fragmentary cross-sectional view showing the tongue and groove design of two adjacent interengaging magnetized strips located on the ferromagnetic plate; and

FIG. 8 is a view similar to that of FIG. 1 but showing one of the magnetized strips partially removed from base location preparatory to reversing the order of priorities with the strip below.

The indicia are shown in broken lines in FIGS. 1 and 8 for illustrative purposes only.

I claim:

The ornamental design for a magnetic variable format appointment board or the like, as shown and described.
